UNITED STATES PATENT OFFICE.

MICHAEL J. WHELAN, OF MUSKEGON, MICHIGAN, ASSIGNOR TO BRUNSWICK-BALKE-COLLENDER COMPANY, A CORPORATION OF DELAWARE.

CLOSET-SEAT.

1,208,869.

Specification of Letters Patent. Patented Dec. 19, 1916.

Original application filed July 14, 1913, Serial No. 778,982. Divided and this application filed October 9, 1914. Serial No. 365,859.

To all whom it may concern:

Be it known that I, MICHAEL J. WHELAN, a citizen of the United States, and a resident of the city of Muskegon, in the county 5 of Muskegon and State of Michigan, have invented certain new and useful Improvements in Closet-Seats; and I do hereby declare that the following description of my 10 said invention, taken in connection with the accompanying sheets of drawings, forms a full, clear, and exact specification, which will enable others skilled in the art to which it appertains to make and use the same.

This invention relates generally to improvements in closet seats and it consists, 15 essentially, in the novel and peculiar combination of parts and details of construction, as hereinafter first fully set forth and described and then pointed out in the claim. 20 In the drawings already referred to which serve to illustrate my said invention more fully, Figure 1 is a vertical, longitudinal section of a closet seat and cover embodying my invention. Fig. 2 is a plan of a closet 25 seat frame before the application of my invention. Fig. 3 is a cross section on line 3—3 of Fig. 2 with my invention applied thereto. Fig. 4 is a fragment of Fig. 1 on an enlarged scale. Fig. 5 is a section on line 30 5—5 of Fig. 2 showing said section in its finished condition. Fig. 6 is a similar section on lines 6—6 of Fig. 2 and Fig. 7 is a section on line 7—7 of Fig. 2.

Like parts are designated by corresponding characters or symbols of reference in all the figures of the drawings.

It is the aim and essence of my invention to produce a seat and cover therefor that is 35 positively immune from germ impregnation; 40 a seat and cover which will always remain sweet; one in which all fecal matter may be removed therefrom without affecting the finish, appearance, or sanitary qualities thereof, and an article of superior appearance and 45 lasting qualities.

Briefly the seat, comprising part of my invention, consists of a wooden frame of the usual appearance, except that it is made of the cheapest class of wood roughly framed 50 together; no attention being paid to the accuracy of joints in the framing nor the closeness of fits in the tenons used in framing. The parts are held together by a few

pegs driven at proper points and no glue is employed. Nor is there any smoothing of 55 the surface attempted, the faces of the frame still showing the saw and tool marks. In this condition the frame is covered with a heavy coating of rubber composition in a plastic state, and the whole is then introduced into a suitable two part vulcanizing 60 mold. This mold is possessed of a cavity 65 the exact duplicate of a finished seat and the two parts thereof are next tightly screwed together, thereby creating a great pressure upon all parts of the mass within 70 the same. Said mold is subjected to great heat for a suitable length of time and then allowed to cool, after which the finished seat is removed therefrom. Said seat now 75 presents a black appearance. The rubber composition (now termed vulcanite) has entirely incased the wood frame and hermetically sealed the same within the coating. All open joints in the framing or tenons and 80 all checks or knots in the wood have been thoroughly filled with the vulcanite, which, at the same time has also actually penetrated the surface of the wood a certain distance, so that the structure is now to all intents and 85 purposes an integral homogeneous mass. The vulcanite may be burnished in a close imitation of ebony and the resultant product is one of handsome appearance and unusual strength and lasting qualities, in addition to 90 being absolutely sanitary. The cover is treated in the same manner, except that its frame is not provided with a central opening as is the seat.

For further details of my invention, attention is now directed to the drawings in which C represents the finished cover and S the similarly prepared seat; V and V' represent the vulcanite covering hermetically inclosing said cover and seat respectively. 95 As the surface of the inner wooden frame is left rough and unfinished, necessarily a multiplicity of minute projections are provided which are embedded in the rubber as it is pressed thereon in a soft plastic state, 100 portions of the rubber being pressed between and other particles being actually pressed into and penetrating the fibers of the projections thus forming an integral bond of mingled wood fibers and rubber 105 which inseparably joins the contacting sur-

faces of the two members or portions of the seat to each other.

F, Fig. 2 indicates the rough wooden seat frame comprising side members 1 and 2 and ends 3 and 4, the whole being framed together by tenons 5, 6, 7, and 8 and dowel pins 9.

The numeral 10 refers to the open joints between the sides and end rails 1 and 2 and 3 and 4. These openings are slightly exaggerated in the drawings and are meant to elucidate the fact that accuracy of workmanship in framing the parts is not necessary. A check in the wood is shown at 11, 15 and a knot at 12 Figs. 2, 5 and 6, the last named of which illustrates how the rubber composition enters these cavities, is vulcanized therein, and actually penetrates the surrounding fiber of the wood.

20 O is a central opening in frame F of seat S, provided for obvious purposes. The interior blank I of cover C is prepared in precisely the same manner as frame F, except that the central opening O is not formed 25 therein.

On the under faces of the seat S and cover C are provided a plurality of vulcanite lined essentially spherical depressions 13 which are provided with necks 14 of smaller 30 diameter. These depressions are provided for the reception of heads 15 of cushioning buttons 16. These buttons are made from comparatively soft rubber and the heads 15 thereof are capable of being compressed sufficiently to pass through necks 14, after which 35 said heads expand and fill the depressions 13, thereby securely retaining said buttons 16 firmly in place. The object of said buttons is to cushion the jar occasioned by 40 dropping the seat upon the top of a closet

bowl or of dropping said cover upon said seat.

Seat S and cover C may be hinged together by any suitably formed hinge H, comprising leaves 20 and 21 and pintle 22.

I wish to call attention to the fact that the practice of my invention is not limited to closet seats alone, but may be applied to other wooden shapes or blanks wherein the practical union of the inner wooden blank and outer vulcanite covering would be advantageous.

While I have herein described the preferred method of carrying my invention into effect, I wish it understood that I may make 55 such changes and alterations as are within the scope of the skilled mechanic and permitted under the doctrine of mechanical equivalents.

Having thus fully described my invention, 60 I claim as new and desire to secure to myself by Letters Patent of the United States:—

A closet seat comprising an annular wood frame composed of a plurality of sections 65 having a rough unfinished surface and loosely fitted and connected together to provide spaces between their contiguous ends, and a coating of rubber composition vulcanized on said frame and filling the spaces 70 between the ends of the sections and the interstices in the surface of the frame.

In testimony whereof I have hereunto set my hand in the presence of two subscribing witnesses.

MICHAEL J. WHELAN.

In the presence of—

F. J. LOEWE,
ADOLPH JOHNSON.
